LOOM

Filed March 22, 1930

INVENTOR,
Edward Bloom,

BY
John Edward
ATTORNEY

UNITED STATES PATENT OFFICE

EDWARD BLOOM, OF PATERSON, NEW JERSEY

LOOM

Application filed March 22, 1930. Serial No. 438,061.

This invention relates to beating-up mechanisms for looms of the type in which the reed is rearwardly yieldable on the lay partly to prevent a "smash" when the beating-up occurs with the shuttle not fully boxed and partly to avoid irregularities in the cloth due to too severe impact of the reed with the fell of the cloth. I utilize spring-including means to resist this rearward yielding and 10 this means is so characterized that when the lay is back greater resistance is opposed than when the lay is forward and the reed abuts the cloth, whereby in the first case, which is when the shuttle is travelling across the lay, 15 the reed will act properly as a guide for the shuttle; but various circumstances, according as one or another type of weave or one or another grade of warp or filling is present, 20 require that the resistance acting to oppose yielding of the reed to the cloth be not fixed or invariable, wherefore an important feature of my invention is that said means shall have its tension adjustable.

Ordinarily, this adjustment of the tension 25 of said means to suit the particular cloth being woven will not appreciably affect the tension when the lay is back and said means is serving to hold the reed up to its work of 30 guiding the shuttle. But for instances where this might occur I provide the system with means to change the ratio of the two resistances of said means, to wit, when the lay is forward and when it is back.

The drawings show the invention,

35 In Fig. 1 when the lay is back and the shuttle is performing its flight; and

In Fig. 2 when the lay is forward.

1 is the loom frame and 2 the lay carried 40 by the lay-swords 3 and movable therewith from the one to the other of the two positions shown. 4 is the shuttle. 5 is the reed pivoted, as at 6, to the lay so that it may swing back from its forward stop, afforded on the lay at 6a. (The reed is here taken as 45 including the reed proper 5a and the frame 5b in which, as usual, it is mounted).

To one of the lay swords is pivoted to move 50 in a vertical plane a detent 7 in the form of a lever having a forwardly extending arm to abut the back of the reed and a rearward arm

longitudinally slotted at 8. On the loom frame is swivelled an abutment 9 which forms supporting means for a spring hereinafter mentioned and also a guide in which is slidable a rod 10 pivoted to a bolt 11 adjustable in the slot 8 of the rearward arm of the detent, and this rod, with an abutment thereon formed by a nut 12 screwed and hence adjustable on the rod and secured by a lock-nut 13, form what I term a thrust member. Between these two abutments a compression spring 14, penetrated by the rod, is arranged, it being of such length that at either limit of motion of the lay it acts through the rod to hold the detent pressing against the reed and hence the latter (normally) pressing against stop 6a.

When the lay is back the spring is under maximum tension, and the detent then keeps the reed up to its work of supporting and hence properly guiding the shuttle in its flight then occurring. When the lay is forward the spring remains still active through the detent to maintain the reed forward against stop 6a but with less pressure, so that the reed if need be may yield to the cloth to avoid production of the mentioned irregularities therein. The force of the spring is variable by adjusting the nut 12.

In some cases it may as indicated be that if the force of the spring is changed so as to suit the particular cloth being woven it will not be proper for insuring proper guidance of the shuttle when the lay is back. Hence I preferably provide the mechanism with means for varying the ratio of such pressures at will. In the example, therefore, a second spring 15, connects hooks (or equivalent) 16 and 17 on the reed and the frame, the latter hook having screwed thereon a nut 18 by which it is supported and by which the tension of the spring may be varied. The nut 12 having been adjusted to produce the necessary pressure of the detent on the reed when the lay is back, if the pressure of spring 14 is then too heavy or too light, when the lay moves forward, to suit the demands of the cloth (always bearing in mind that the inertia of the reed as the lay stops its forward beat is a factor at this time) the adjustment

of the tension of spring 15 may be resorted to to correct this condition.

Having thus fully described my invention what I claim is:

5 1. A beating-up mechanism for looms comprising a lay movable forwardly and backwardly, a rearwardly yielding reed on the lay and spring-including means to oppose to the reed greater resistance against rearward displacement when the lay is back than when the lay is forward, said reed being normally urged forwardly by said means when the lay is forward and the reed abuts the cloth but otherwise free at that time to yield backwardly.

10 2. A beating-up mechanism for looms comprising a lay movable forwardly and backwardly, a rearwardly yielding reed on the lay, and adjustable-tension spring-including means to oppose to the reed greater resistance against rearward displacement when the lay is back than when the lay is forward, said reed being otherwise free to yield backwardly when the lay is forward and the reed abuts the cloth.

15 3. A beating-up mechanism for looms comprising a lay movable forwardly and backwardly, a rearward yielding reed on the lay, a lever fulcrumed on the lay and engaged with and movable by the reed on yielding of the latter, and adjustable-tension spring-including means to oppose to the lever greater resistance against movement by the reed when the lay is back than when the lay is forward.

20 4. A beating-up mechanism for looms comprising a lay movable forwardly and backwardly, a supporting means with reference to which the lay is so movable, reciprocatory means on the lay comprising a rearwardly yielding reed and a thrust member guided by the supporting means, and a spring operatively interposed between said means and opposing movement of the reciprocatory means in the direction corresponding to that in which the reed is yieldable.

25 5. A beating-up mechanism for looms comprising a lay movable forwardly and backwardly, a supporting means with reference to which the lay is so movable, reciprocatory means on the lay comprising a rearwardly yielding reed and a thrust member guided by the supporting means, and a spring operatively interposed between said means and opposing movement of the reciprocatory means in the direction corresponding to that in which the reed is yieldable, one of said means having means to vary the tension of the spring.

30 6. A beating up mechanism for looms comprising a forward and backward moving lay, a rearwardly yielding reed on the lay, and means to oppose rearward yielding of the reed and exerting less resistance to such yielding when the lay moves forward than

when the lay moves back, said mechanism having means to change the ratio of such resistances.

35 7. A beating up mechanism for looms comprising a forward and backward moving lay, a rearwardly yielding reed on the lay, and means to oppose rearward yielding of the reed and exerting less resistance to such yielding when the lay moves forward than when the lay moves back, said mechanism having spring-including means to change the ratio of such resistance.

In testimony whereof I affix my signature.

EDWARD BLOOM.
